UNITED STATES PATENT OFFICE.

JAMES A. HYDE, OF MILLERTON, NEW YORK.

SIGNAL-LANTERN.

SPECIFICATION forming part of Letters Patent No. 415,205, dated November 19, 1889.

Application filed December 8, 1888. Serial No. 292,977. (No model.)

To all whom it may concern:

Be it known that I, JAMES A. HYDE, of Millerton, in the county of Dutchess and State of New York, have invented a certain new and 5 useful Improvement in Signal - Lanterns, whereof the following is a description, reference being had to the accompanying drawings, where—

Figure 1 is a side view of a lantern embodying said improvement with the door of the signal-tube open. Fig. 2 is a detail view of a portion of said lantern in vertical section through the center of the signal-tube with the door thereof closed. Fig. 3 is a bottom view 15 of the lantern. Fig. 4 is a view of the lower part of the lantern in section on plane $x x$.

The letter a denotes an uncolored glass globe of a common hand-lantern; b denotes the ordinary metallic frame above the same; 20 c denotes the ordinary metallic frame below the same, and d denotes a wire guard for the glass globe. The horizontally-arranged brace-bar d' of the wire guard has its ends secured to the sides of the signal-tube, and serves to 25 hold the tube in position.

The letter e denotes a signal-tube, the rear portion of which is closely fitted to the contour of the glass globe. It has within it a colored glass plate f —commonly red glass. It 30 has on the outer or front end a door g of any suitable construction, which may be opened or closed, and in case it has a hinged door it

may have a spring-catch to keep it closed, such as is indicated in Fig. 1.

When the lamp inside the lantern is lighted 35 and the door g is closed, the lantern serves as an ordinary lantern, but by opening the door g the signal-tube will throw out a colored light, and the lantern may be used for appropriate signaling purposes. The signal-tube is held in position by connection to the brace-bar d' , as heretofore stated, and by being attached to the upper and lower frames b' and c' .

In the bottom of the lantern there is formed 45 a magazine h , intended to contain that kind of torpedoes used for signaling purposes on railways. This magazine is provided with some suitable door, the character of which is not essential, and in the drawings, Fig. 4, it is 50 shown as a sliding door i .

I claim as my improvement—

In a signal-lantern, the combination, with the globe, the top and bottom metallic frames, and the wire guard, of a signal-tube provided 55 with a signal-glass, and a door to close the tube, and a horizontally-arranged holding and brace wire secured to the wire guard with its ends fastened to the signal-tube, substantially as described, and for the purpose specified.

JAMES A. HYDE.
